METHOD OF AND APPARATUS FOR LOCATING WATER LEAKAGES INTO WELLS

George H. Ennis, Long Beach, Calif., assignor of
one-half to Robert V. Funk, Long Beach,
Calif.

Application December 16, 1936, Serial No. 116,164

17 Claims. (Cl. 175—183)

My invention relates to the oil producing industry and particularly to a simple and improved method whereby the point of leakage of fluid, such as water, into a well may be accurately determined.

In order that the features and advantages of my invention may be better understood I will briefly refer to the art to which my invention appertains. In the drilling of an oil well many different formations are penetrated, some of which contain water, and to exclude such water from the well so that the oil when the well is placed on production will not be contaminated, one or more well casings are installed in the well and cemented in place at their lower ends. Sometimes leakages occur in the well casing or at the point cemented at the lower end thereof which results in the production of an undesirable emulsion. At other times a water sand is positioned between two producing oil sands with the result that an emulsion is formed. Also when an oil sand becomes exhausted, or nearly exhausted, water flows into the well.

It has been the practice when a well produces water to determine the point of leakage of water into the well and to then seal the wall of the well at a suitable point in order to exclude water. It is an object of this invention to provide a method whereby the point of entrance of water into a well may be located so that by a suitable cementing process the water may be excluded.

Processes in general use in the art prior to my invention all require the depositing of a special material in the well in order that the test may be made. This, to say the least, requires considerable time as compared to my process and is much more expensive. It is an object of my invention to provide a method of the character pointed out in which no special material need be deposited in the well, but on the contrary the test is made with the fluid or material in the well which remains there from a previous operation whether the material in the well be a column of low gravity oil or emulsion, water, or rotary mud.

I have discovered that if a well which is being pumped is allowed to stand for a period of time and that therefore the head of the column of oil or emulsion in the well is reduced to allow fluid to flow into the well from the surrounding formation, that this fluid has different electro-chemical characteristics which may be very small and in most instances a matter of microunits. I have found that by the use of a very sensitive recording apparatus employed in an electrical circuit

and adapted to record either microvolts or microamperes, that these very small differences between the fluid which has been allowed to stand in the well, and which, for the purpose of identification, I call "dormant fluid", or "dormant material", and the fluid which is allowed to flow into the well by the bailing process, and which, for the purpose of identification, I term "live fluid", may be measured and in this way the point of leakage located. This difference in electro-chemical qualities or characteristics of the live fluid may be the result of different causes. For example, when fluid is allowed to stand in the well any gas contained therein will tend to levitate and solid particles tend to gravitate. This results in a dormant material of different electro-chemical characteristics than the live fluid. Also, the live fluid entering the well may be of a different temperature from the dormant fluid in the well, and in addition to this the fluid entering the well may cause an electromotive force to be set up between moving liquids and solids, both of which result in electro-chemical characteristics in the live fluid which are different from those of the dormant fluid.

In practicing my invention I may use alternative methods. For example, assuming that the well has been placed on the pump and is pumping an emulsion; I remove the pumping apparatus from the well in a very careful manner so that the well fluid will not flow backwardly into the surrounding formations. I then allow the well to stand for a period of time so that the fluid will become dormant. I then by use of very sensitive apparatus test the electro-chemical qualities of the fluid in the well and preferably make a record thereof. This testing apparatus may consist of an electrical circuit including two electrodes which are lowered into the well. The electrical circuit and electrodes may be of such a character that the electrodes and the fluids in the well form a voltaic cell, and the potential difference between the electrodes is measured. On the other hand, the electrical circuit may be arranged to produce a current flow through the fluid in the well and between the electrodes, thus measuring the resistance or conductance of the fluid. After the initial test is made fluid is then caused to flow into the well from the surrounding formation such as by lowering the head of oil by the bailing process. After this step the testing process is repeated and a record made. Where water has entered the well, the electro-chemical qualities will be different from those of the dormant fluid in the well, and this will be

clearly visible on the recording instrument or on the records which are made. Where this difference in electrical characteristics occurs which may be greater current flow, less current flow, greater voltage, or less voltage, the water has entered the well and by cementing at this point may be excluded therefrom. In the alternative process of my invention no test is made prior to the bailing step, but the first step in the process is to bail off the material in the well so as to cause an ingress of fluid. A test is then made, as pointed out heretofore. Thereafter an additional bailing operation may be performed to cause an ingress of additional live fluid. Another test is then made and the records obtained from the two tests are compared, and where the differences in electro-chemical characteristics occur, this is the point of entrance of fluid into the well.

I have further discovered that where there is a water leakage into a well the electro-chemical characteristics of the fluid or material in the well adjacent this point where the water leakage exists are different from the electro-chemical characteristics of other material in the well which has been allowed to age or become dormant. By the use of my invention it is possible to locate the leakage point without causing live fluid to flow into the well; and it is therefore an object of my invention to provide a method of locating water leakages in which it is unnecessary to place any special materials, such as electrolytes, in the well, and in which a bailing step is unnecessary.

One explanation of this condition is that water is a better conductor of heat than oil, and therefore the formation temperature is better transmitted to the well. The heat of the water formation therefore is transmitted or radiated to the material in the well which lies immediately adjacent the water bearing formation, and this difference in temperature is sufficient to produce small electro-chemical differences between this material lying adjacent the water bearing formation and material in other parts of the well.

The method of my invention in its preferred form depends on the measurement or indication of microvolts or microamperes, and it is therefore very necessary to maintain uniform or constant the various factors which affect the method so that the only variable value in the circuit which I employ is caused by the differences in the electrochemical characteristics of the material or fluid in the well. I have found it to be quite essential to maintain a uniform relationship between electrodes which I employ in my process and which I lower into the well in order to determine the electro-chemical characteristics of the material or fluid in the well, and the wall of the well. I find it highly desirable to cause the electrodes to accurately follow the contour of the well in order that conditions and relationships may be maintained constant. If the electrodes do not have a uniform position with respect to the axis of the well potential differences between the electrodes in the wall of the well will change and electrical or electro-chemical leakages will occur to different extents, which naturally affect the values of the readings obtained at the surface of the ground, with the result that deviations in the readings are produced by causes other than electro-chemical qualities or characteristics of the fluid in the well. It is accordingly an object of my invention to provide a method of locating water leakages in a well in which movable electrode means employed in the process is maintained in a uni-

form relationship to the axis or contour of the well when it is moved into various positions along the well.

A further object of my invention is to provide a method of the character pointed out in which the pair of electrodes is maintained substantially concentric to and in alignment with the axis of the well for all positions into which the electrodes are moved along the well.

The term "electro-chemical" as employed throughout this specification is intended to include both the electrical action or reaction which results from the forming of a voltaic cell in the material or well fluid or from the passage of an electric current through or the impressing of a potential difference on the well fluid.

My invention may be applied to wells which are being pumped, to wells which are filled with mud and are not flowing, and also to wells which flow by reason of subterranean pressures. In the latter case the well is first capped and thereafter the test of my invention is made.

Other objects and advantages of my invention will be pointed out in the course of the following detailed description of various forms in which I have practiced my invention. It should be understood, however, that various modifications and alterations may be made without departing from the spirit and scope of my invention, that the detailed description is intended to instruct those skilled in the art as to the manner in which my invention may be practiced, and that in view of these facts I do not wish or intend that my invention be limited to the precise details described herein, but wish my invention to be construed in accordance with the scope of the appended claims.

Referring to the accompanying drawings which diagrammatically illustrate apparatus capable of performing the methods of my invention:

Fig. 1 is a diagrammatic view illustrating my apparatus in use in a well.

Fig. 2 is a diagrammatic view of a graph, chart, or curve made by the recording instrument employed as a part of the apparatus shown in Fig. 1, which curve was made from a test of the well material prior to the bailing process and prior to the entrance of live fluid into the well.

Fig. 3 is a view similar to Fig. 2 showing the curve obtained in a test of the electro-chemical qualities of the contents of the well after live fluid has been caused to enter the well.

Fig. 4 is a view similar to Fig. 1 showing an alternative form of apparatus.

Fig. 5 is a vertical sectional view illustrating a form of electrode construction which I may employ in my invention.

Fig. 6 is a sectional view taken on the line 6—6 of Fig. 5.

Referring to the drawings in detail, and particularly Fig. 1, the numeral 11 represents a well in which a well casing 12 has been installed. The lower end of the well casing 12 has been cemented at 14 to a shale 15 in order to seal from the well all formations above the shale 15. At the lower part of the well 11 and below the shale 15 are sand formations 16, 17 and 18 which are separated by shales 19 and 20. For the purpose of illustrating the invention, it will be assumed that the formations 16 and 18 produce oil and that the intermediate formation 17 produces water, with the result that the oil which is pumped from the well 11 is in the form of an emulsion. In order to test this well it is first necessary to

remove the pumping apparatus from the well and to thereafter allow the fluid in the well to seek its own level, as indicated at 21. When this is done the additional steps of the process of my invention may be performed by the apparatus which I will now describe. The numeral 25 represents a flexible cable which extends over a sheave 26 from a drum 27 on which this cable may be wound. The cable 25 includes a pair of conductors 29 and 30. The ends of these conductors 29 and 30 are connected to electrodes 31 and 32. In the form of apparatus illustrated in Fig. 1 these two electrodes and the fluid in the well constitute a voltaic cell, and therefore these electrodes 31 and 32 in reality constitute the plates of a one-cell battery. It is desirable to use different metals for these plates which are electro-chemically opposite to each other, such, for example, as cadmium and antimony.

At the surface of the ground the conductors 29 and 30 are connected to a recording device 34 which is designed to record the potential difference between the electrodes 31 and 32 or the changes in potential difference between these two electrodes at different positions in the well. As pointed out heretofore, it is necessary to use an extremely sensitive recording device, and the one illustrated herein is a microvoltmeter adapted to record from zero to one hundred microvolts. In the practice of my invention, by use of a potentiometer circuit I balance the recording needle 35 to a central position on the scale 36 so that a difference in electro-potential between the electrodes 31 and 32 in either direction, that is, in increase or decrease, may be recorded on the recording device 34. The potentiometer circuit employs an adjustable rheostat, including a resistance 37 and an adjustable contact 38, one end of the resistance 37 being connected to the conductor 30, and the other end being connected to a source of energy, such as a battery 39. The adjustable contact 38 is connected to the recording device 34 and is adjustable in order to vary the resistance in the circuits. The battery 39 is connected through a potentiometer circuit conductor 41 to the conductor 29 as indicated at 42, and includes a rheostat in the form of a resistance 43 and an adjustable contact 44.

The recording meter 34 is only diagrammatically illustrated as are the other parts of the apparatus of my invention, and this recording meter may be any well known type which will automatically produce a chart of the current flows or voltages, such as is shown in Fig. 2. Likewise, the recording device may be merely a meter which is observed by the operator and the different indications written down, from which a chart, graph, or curve may be plotted.

The electrode apparatus which I prefer to use is illustrated in Figs. 5 and 6. The cable 25 is secured by a connection 78 to an electrode apparatus which supports the electrodes 31 and 32. This apparatus includes an upper shaft 71 and a lower shaft 72, the upper shaft having supporting arms 73, and the lower shaft having supporting arms 74 which extend toward each other and respectively support plates 75 and 76 to which the electrodes 31 and 32 are secured. Mounted on the shafts 71 and 72 are hubs 78 and 79 which are forced toward each other by a spring 80 compressed between the connection 60 and the hub 78 and a spring 81 compressed between a nut 82 mounted on the end of the shaft 72 and the hub 79. Connected to the hubs 78 and 79 are centralizing bars 83 which bow outwardly

at their central portions, as shown in Fig. 5, for engagement with the wall of the well or the casing which may be installed in the well. These centralizing arms 83 are resilient so that they may accommodate themselves to different diameters of wells. The springs 80 and 81 always hold the central portions of the centralizing arms 83 outwardly so that the wall of the well will be engaged.

As is illustrated best in Fig. 5, the axis of the well is indicated by the point 84. The centralizing arms 83, being caused to engage the wall of the well, always maintain the electrodes 31 and 32 in a predetermined position with respect to the axis of the well. The distance A and the distance B which represent the distances between the electrode 31 and the wall of the well and the electrode 32 and the wall of the well are always maintained uniform and of the same length. Where the diameter of the well is smaller the distances A and B will, of course, be smaller, and where the diameter of the well is larger the distances A and B will, of course, be larger. However, in a well of a given size these distances A and B are maintained substantially uniform, with the result that the electrical or electro-chemical relationship between these electrodes and the wall of the well will be maintained constant or uniform, and there will be no deviating or changing influence on the recordings obtained at the surface of the ground due to any changes in value other than that produced by the electro-chemical qualities of the material or fluid in the well. The electrode apparatus is so designed that the electrodes 31 and 32 are accurately guided along the axis of the well as the apparatus is moved either upward or downward in the well, and therefore the electrodes are caused to follow the contour of the well even though it deviates considerably from vertical, and in this way the relationship between the electrodes in the well is maintained so that there will be no fluctuations which would cause false indications of the recording apparatus.

Having described the apparatus, I will now explain the method of my invention which is practiced by this apparatus. As pointed out heretofore, if the well is one which is being pumped the pump is removed and the oil allowed to seek its own level or natural head. The first step in the process is to allow the well to stand for a sufficient period of time to allow the fluid in the well to become dormant. The term "dormant", it will be understood, is merely a relative term and signifies that the fluid or material in the well has stood for a sufficient length of time so that the electro-chemical qualities of the fluid are different from those of the live fluid which enters the well during the bailing process, as will be explained shortly. The period of time which the contents of the well requires to become dormant may change in different wells, but in practice I usually allow the well to set from two to three hours. When the well has set for this period of time and the fluid has become dormant, I then perform a test of the electro-chemical qualities of the contents of the well. This is done in the following manner. The electrodes 31 and 32 are lowered into the well, and when these electrodes enter the liquid an electro-potential difference is set up between these electrodes 31 and 32 and the needle 35 is deflected. I then adjust the pointers 38 and 44 of the rheostats in order that the potentiometer circuit will balance the current flows in the circuit comprising the conductors 75

29 and 30 and will bring the needle 35 to a substantially central position on the scale 36. The electrodes 31 and 32 are then slowly lowered into the well and the deflections of the needle 35 observed, or if the recording device is one which produces a chart or curve, the curve is produced in accordance with that illustrated in Fig. 2.

As explained heretofore, the electrodes are caused to follow the contour or axis of the well 10 and are maintained predetermined distances A and B from the wall of the well. In this way the only change in value in the performance of the method of my invention is that which is caused by changes in electrical or electro-chemical characteristics of the material or fluid in the well.

Referring to Fig. 2, the horizontal lines represent the depth of the electrodes 31 and 32 in feet, the first heavy line being 4300 feet, the second heavy line being 4400 feet, and the intermediate 20 light lines representing 10 feet each. The vertical lines are merely arbitrary and for the purpose of reference, since in my process the amount of deflection of the needle 35 or the difference in electro-potential or the current flow is immaterial except insofar as the electro-chemical characteristics or qualities recorded in the two tests are concerned when comparison is made, as will be explained shortly. Usually the curve produced from the original test is substantially 30 as shown by the curve 50 in Fig. 2 and fluctuates on either side of the zero positions on the chart, it being understood that the zero position is merely the central position of the needle 35 on the scale 36, to which position it is adjusted by adjusting the resistance in the circuits, as pointed out heretofore.

The apparatus is then removed from the well, the graph removed from the recording apparatus, and a new piece of graph paper installed, 40 or turned back and different color ink used for next curve. Live fluid is then caused to enter the well by lowering the liquid head in the well. This is conveniently done by a bailing process. The well then seeks its own level and in so doing 45 live fluid will flow into the well. In this instance water will flow from the formation 17 into the well 11. A second test of the electro-chemical qualities of the contents of the well is then made in accordance with the previous test without, 50 however, changing the set-up of the apparatus, and a curve or chart as shown in Fig. 3 is made. Where live fluid has entered the well the curve 50 and the curve 51 shown in Fig. 3 will be different, since the electro-chemical qualities of 55 the live fluid are different from those of the dormant material in the well, which differences are very small but are recorded on the microrecording means 34. As illustrated in Fig. 3, the curve 51 has a peak 52 which is not present in the curve 60 50, and therefore the point of entrance of water into the well is as shown on the chart of Fig. 3 at approximately 4520 feet. If it is desired to have additional corroboration of the point of entrance of water of the bailing process, testing may 65 be repeated and the peak will be increased as indicated by dotted lines 53. With the information given by the charts shown in Figs. 2 and 3 and the curves 50 and 51 thereof, the water sand 17 may be sealed from the well. Thereafter water will not 70 leak into the well and there will be no emulsion.

In the method of my invention which does not involve the bailing step I follow the same practice in allowing the fluid or material in the well to become dormant, and therefore the electro-chemical characteristics thereof are different 75

from the live fluid in the formation. As pointed out heretofore, a difference in temperature will produce a difference in the electro-chemical qualities of the fluid or material in the well. At those locations directly opposite the water bearing formation the temperature of the water bearing formation will be transmitted to the material in the well and raise its temperature above the temperature in the material in other parts of the well. For example, if the temperature in a water bearing formation is 180° F. and the temperature of the material in the well is 178° F., the temperature of the material in the well adjacent the water bearing formation will be raised by heat transmission to approximate 179° F. There will, therefore, be a slight difference in the electro-chemical qualities of the fluid in the well adjacent the water bearing formation and other fluid in the well. Although this difference may be slight, it is possible to record it by the use of a microammeter 15 or a microvoltmeter.

In the form of my invention illustrated in Fig. 4 various parts may be the same as illustrated in Fig. 1 except that in Fig. 4 the apparatus measures the resistance or conductance of the contents of the well rather than the potential difference between the electrodes 31 and 32, and the electrodes 31 and 32 need not be made from dissimilar metals. The only difference in the electrical hook-up is the use of a battery 60 in 20 the conductor 30, and when used the potentiometer circuit is used to balance the current flow so that the recording needle 35 will occupy a central position on the scale 36. When the electrodes 31 and 32 are lowered into the well the changes 25 in resistance or conductance of the well contents between these two electrodes change in accordance with the electro-chemical characteristics or qualities of the material, and since this material forms a part of the electrical circuit these differences will be recorded on the recording means 34. In the performance of the process the various steps which are performed may be the same as the method explained in connection with Fig. 1 except that the curves produced will not be the 30 potential differences or current flow produced by the voltaic cell, but will be the difference in resistance of the material at various points. The live fluid, having different electro-chemical qualities from the dormant fluid in the well, will have 35 a different resistance or conductance, and therefore the point of entrance of water into the well may be located.

As pointed out heretofore, a further form of my method does not require the performance of 5 a test before bailing and may be practiced by first allowing the fluid to become dormant, then bailing liquid from the well in order to cause an ingress of live fluid, and then the making of a test, as pointed out heretofore. The first test will 6 produce a curve somewhat as illustrated in Fig. 3 including a peak 52. After this test is made the well is then again bailed and another test is made, and where the water has leaked into the well there will be a larger peak, such as indicated at 65 53 in Fig. 3, which in turn indicates the point of leakage into the well.

In the practice of my invention it is unnecessary to introduce special materials, such as electrolytes, into the well, but the fluid or material 7 which has remained in the well from a previous operation may be used. By this I mean after the well has been placed on the pump the oil or emulsion which remains in the well when the pump is removed may be used. If the well is a 7

flowing well, this well may be capped and the material in the well may be employed. The process of my invention is a great saving over the prior art not only so far as time is concerned, 5 but also in expense. The depositing of electrolytes or other materials in the well very often amounts to considerable. In the practice of my invention the cost of locating water leakages may be reduced to one-half or one-third of the cost 10 where prior art methods are employed.

I believe my invention to be broadly new and based on a discovery and principle of operation totally different from the prior art, and I therefore wish my invention to be broadly construed 15 in accordance with the appended claims.

I claim as my invention:

1. A method of locating the point of entrance of water into a well, which method includes the steps of: testing the electro-chemical qualities of 20 the residual material in the well at different levels in the well without the addition of any substance to the material in the well; causing an ingress of connate fluid into the well; and again testing the electro-chemical qualities of the material in the 25 well at different levels to determine the point of entrance of said connate fluid.

2. A method of locating the point of entrance of water into a well, which method includes the steps of: testing the electro-chemical qualities of 30 the residual material which has remained in the well from previous normal operations therein at different levels in the well; causing an ingress of connate fluid into the well; and again testing the electro-chemical qualities of the material in the 35 well at different levels to determine the point of entrance of said connate fluid.

3. A method of locating the point of entrance of water into a well, which method includes the steps of: allowing the residual material in the 40 well to become dormant; testing the electro-chemical qualities of said dormant material at different levels in said well and making a record thereof; causing live fluid to flow into said well; again testing the electro-chemical qualities of 45 the contents of the well at different levels, and making a record thereof; and determining, by comparison of said records, the point of entry of fluid into said well.

4. A method of locating the point of entrance of 50 water into a well, which method includes the steps of: allowing the residual material in the well to remain in said well for a sufficient length of time for its electro-chemical qualities to change from that of live fluid; testing the electro-chemical qualities of said dormant material 55 at different levels in said well and making a record thereof; causing live fluid to flow into said well; again testing the electro-chemical qualities of the contents of the well at different levels, and 60 making a record thereof; and determining, by comparison of said records, the point of entry of fluid into said well.

5. A method of locating the point of entrance of 65 water into a well, which method includes the steps of: removing from the well a part of the residual material which has remained therein from a previous normal drilling or production 70 operation, and without the addition of any substance to the material in the well, thus causing live fluid to flow into said well; testing the electro-chemical qualities of the contents of the well at different levels and making a record thereof; again removing material from said well to cause 75 additional live fluid to flow into said well; again testing the electro-chemical qualities of the con-

tents of said well at different levels, and making a record thereof; and determining the point of entrance of said live fluid in said well by comparing said records.

6. A method of locating the point of entrance 5 of water into a well, which method includes the steps of: allowing the residual material in said well to become dormant; removing from the well a part of the material therein, thus causing live fluid to flow into said well; testing the electro-chemical qualities of the contents of the well at different levels and making a record thereof; again removing material from said well to cause additional live fluid to flow into said well; again testing the electro-chemical qualities of the contents of said well at different levels, and making a record thereof; and determining the point of entrance of said live fluid in said well by comparing said records.

7. A method of locating the point of entrance 20 of water into a well, which method includes the steps of: allowing the residual material in said well to become dormant; testing the electro-chemical qualities of the contents of the well at different levels and making a record thereof; again removing material from said well to cause additional live fluid to flow into said well; again testing the electro-chemical qualities of the contents of said well at different levels, and making a record thereof; and determining the point of entrance of said live fluid in said well by comparing said records.

8. A method of locating the point of entrance 25 of water into a well, which method includes the steps of: allowing the residual material in the well to become dormant; lowering a pair of electrodes of dissimilar metal into said well to form a voltaic cell consisting of said electrodes and the material in said well adjacent said electrodes; maintaining a uniform relationship between the wall of said well and said electrodes; and measuring the electrical characteristics produced by said voltaic cell.

9. A method of locating the point of entrance 30 of water into a well, which method includes the steps of: allowing the residual material in the well to remain in said well for a sufficient length of time for the electro-chemical qualities to change and for the adjacent water bearing formation to affect the electro-chemical qualities 35 of the material in said well adjacent to said water bearing formation; lowering a pair of electrodes of dissimilar metal into said well to form a voltaic cell consisting of said electrodes and the material in said well adjacent said electrodes; maintaining a uniform relationship between the 40 wall of said well and said electrodes; and measuring the electrical characteristics produced by said voltaic cell.

10. A method of locating the point of entrance 45 of water into a well, which method includes the steps of: allowing the residual material in the well to become dormant; lowering a pair of spaced electrodes into said well; maintaining a uniform relationship between the wall of said well and said electrodes; and measuring the 50 electrical characteristics of the material between said electrodes.

11. A method of locating the point of entrance 55 of water into a well, which method includes the steps of: allowing the residual material in the well to remain in said well for a sufficient length of time for the electro-chemical qualities to change and for the adjacent water bearing formation to affect the electro-chemical qualities 60 of the material in said well adjacent to said water bearing formation; lowering a pair of electrodes of dissimilar metal into said well to form a voltaic cell consisting of said electrodes and the material in said well adjacent said electrodes; maintaining a uniform relationship between the 65 wall of said well and said electrodes; and measuring the electrical characteristics produced by said voltaic cell.

of the material in said well adjacent to said water bearing formation; lowering a pair of spaced electrodes into said well; maintaining a uniform relationship between the wall of said well and said electrodes; and measuring the electrical characteristics of the material between said electrodes.

12. A method of locating the point of entrance of water into a well, which method includes the 10 steps of: allowing the residual material in the well to become dormant; lowering a pair of electrodes of dissimilar metal into said well and to form a voltaic cell consisting of said electrodes and the material in said well adjacent said electrodes; causing said electrodes to follow the contour of said well when the same are lowered in order to maintain a uniform relationship between the wall of said well and said electrodes; and measuring the electrical characteristics produced by said voltaic cell.

13. A method of locating the point of entrance of water into a well, which method includes the steps of: allowing the residual material in the well to remain in said well for a sufficient length of 25 time for the electro-chemical qualities to change and for the adjacent water bearing formation to affect the electro-chemical qualities of the material in said well adjacent said water bearing formation; lowering a pair of electrodes of dissimilar 30 metal into said well to form a voltaic cell consisting of said electrodes and the material in said well adjacent said electrodes; causing said electrodes to follow the contour of said well when the same are lowered in order to maintain a uniform relationship 35 between the wall of said well and said electrodes; and measuring the electrical characteristics produced by said voltaic cell.

14. A method of locating the point of entrance of water into a well, which method includes the 40 steps of: allowing the residual material in the well to become dormant; lowering a pair of spaced electrodes into said well; causing said electrodes to follow the contour of said well when the same are lowered in order to maintain a uniform relation-

ship between the wall of said well and said electrodes; and measuring the electrical characteristics of the material between said electrodes.

15. A method of locating the point of entry of fluid into a well, comprising: discontinuing normal operations in the well; making a first observation of the status of consecutive points in the content of a well in static condition without adding substance to the content of the well from the surface; changing said status by causing a flow of fluid into the well from the formation in which the well is formed; making a second observation of the status of consecutive points in the content of the well; and determining the location of the point of entry of said fluid into the well by comparing said second observation with said first observation and noting where the status of content of the well has been changed by said entry of fluid.

16. A method for locating the point of entry of fluid into a well, comprising: discontinuing normal operations in the well and then making consecutive tests of the electro-chemical qualities of the fluid remaining in the well without placing of any substance in the well from the surface, said tests including a step of causing entry of fluid into the well from the adjacent formation preceded and followed by tests of the electro-chemical qualities of the fluid in the well, and comparing said tests.

17. A method for locating the point of entry of fluid into a well in which drilling operations in the presence of mud have been carried on, comprising: discontinuing the normal operations in the well and then making consecutive tests of the electro-chemical qualities of the fluid comprising mud remaining in the well without the placing of any substance in the well from the surface, said tests including a step of causing entry of fluid into the well from the adjacent formation preceded and followed by tests of the electro-chemical qualities of the fluid and mud in the well, and comparing said tests.

GEORGE H. ENNIS.

CERTIFICATE OF CORRECTION.

Patent No. 2,184,338.

December 26, 1939.

GEORGE H. ENNIS.

It is hereby certified that error appears in the printed specification of the above numbered patent requiring correction as follows: Page 1, second column, line 7, for "he" read the; page 2, second column, line 47, for the word "wall" read well; and that the said Letters Patent should be read with this correction therein that the same may conform to the record of the case in the Patent Office.

Signed and sealed this 20th day of February, A. D. 1940.

(Seal)

Henry Van Arsdale,
Acting Commissioner of Patents.
